UNITED STATES PATENT OFFICE.

JEROME N. ADAMS, OF MALVERN, ARKANSAS.

RAIL-JOINT.

1,199,146.

Specification of Letters Patent. Patented Sept. 26, 1916.

Application filed March 2, 1915. Serial No. 11,472.

To all whom it may concern:

Be it known that I, JEROME N. ADAMS, a citizen of the United States, residing at Malvern, in the county of Hot Spring and 5 State of Arkansas, have invented certain new and useful Improvements in Rail-Joints, of which the following is a specification.

This invention relates to rail joints, the 10 primary object being to eliminate the use of fish plates, etc., through the medium of which, the proximate ends of the rails are usually held in place.

Another object of the invention is to 15 complementally reduce the proximate ends of the rails, to permit sliding engagement of the rails for providing a continuous tread, without the instrumentality of hoisting mechanism, etc.

20 Other objects as well as the nature, characteristic features and scope of my invention will be more readily understood from the following description taken in connection with the accompanying drawings and 25 pointed out in the claims forming a part of this specification.

Referring to the drawings: Figure 1 is 30 a fragmentary perspective view of one of the rail sections constructed in accordance with my invention, Fig. 2 is a similar view of the complementary section, and Fig. 3 is a fragmentary side elevational view of the conjoined sections.

In the drawings wherein is illustrated the 35 preferred embodiment of this invention, a pair of sections 5 and 6 are provided. Each of the sections 5 and 6 is provided with a head 7, web 8 and base flange 9, which may be of the usual or any desired configuration 40 except at the terminals of each section. The terminals of each section, are of course, especially formed, in order to provide the peculiar formation of joint hereinafter described.

45 The section 5 of the rail has a portion of the lower end of its web removed to provide an inclined face 10, which tapers from one of the terminals of said section, toward the opposite terminal, subsequently issuing in 50 the lower edge of the web, and meeting the inclined face 11 of the base flange of said section. Abutments 12 extend laterally from the opposite sides of the web, at approximately the jointure of the inclined 55 face 11 and the inclined face 10, and are of

an appreciable thickness so as to preclude possibility of mutilation when slidably engaged with the opposite section as will be more fully hereinafter set forth.

The section 6, has its base flange extended 60 considerably beyond the terminal of the head 7 and web 8 thereof and conforms to the configuration of the section 5. The free terminal of the base flange 9 is inclined as indicated at 13 toward its free end, so as 65 to provide an edge 14 on its terminal, to facilitate engagement of the sections 5 and 6 without the instrumentality of any means other than those necessary for exerting pressure upon the sections so as to advance 70 the same toward each other. A pair of splice bars 15 extend outwardly from the web 8, and are offset from the latter so as to provide sufficient space to accommodate the web 8 of the section 5 therebetween. 75

The free terminals of the splice bars 15 extend slightly beyond the inception of the inclined face 13, so as to engage the abutments 12 when the sections 5 and 6 are engaged. By providing the splice bars 15, it 80 will be appreciated that lateral displacement of the rails is positively precluded, that is, independent lateral displacement of the rail sections. Furthermore, the web 8 of the section 5 is provided with a plurality 85 of openings 16 therein, which are adapted to register with openings 17 in the splice bars 15, said openings being adapted to receive bolts 18 therein, so as to positively retain the rail sections from displacement. 90 In use therefore, it is seen that the sections 5 and 6 are engageable by merely advancing the same toward each other so as to engage the web 8 of the section 5 between the splice bars 15, the head 7 of the 95 section 5, being adapted to rest upon the upper margin of the splice bars 15. This obviously will eliminate the use of hoisting mechanism which is usually required in order to aptly fit the rail sections together 100 where a joint is used.

It will be understood that the above description and accompanying drawings comprehend only the general and preferred embodiment of my invention and that 105 various minor changes in details of construction, proportion and arrangement of parts may be made within the scope of the appended claims without sacrificing any of the advantages of my invention.

Having thus fully described my invention what I claim as new and desire to secure by Letters Patent is:

1. A rail joint comprising a plurality of rail sections having portions of the meeting ends at their base flanges cut away to provide complementary flat surfaces adapted to be superposed one upon the other, said surfaces inclining at an angle from the juncture of the rail webs and base flanges and widening out toward their bases to provide enlarged bearing surfaces, splice bars carried at one end of each section and projecting beyond the inclined surface thereof, and the base flanges of the adjacent section terminating abruptly to provide abutment means for said splice bars.
2. A rail joint comprising a plurality of rail sections having their base flanges inclined to provide complementary meeting faces, one of said sections having the lower edge of its web portion inclined and meeting with the inclined surface of the base flange to form an inclined bearing surface tapering from its base, the other of said sections having a portion of its tread and web portion removed to provide a seat for the inclined surface of the first section, and means carried by the second section and supported

upon the inclined surface thereof for engaging and retaining the web of the first section.

3. In a rail joint, the combination with a rail section having a portion thereof removed to provide a flat surface extending beyond the web of said section and inclining at an angle from the juncture of the rail web and base flange thereof, of splice bars carried by said section on opposite sides of said rail web and forming a continuation of the latter, and a meeting rail adapted to be engaged by said splice bars and having a portion of its web and base flange removed to provide an inclined flat surface complementary to the surface of the first section, said flat surfaces adapted to be superposed one upon the other and widening toward their bases to provide greater bearing surfaces, one of the surfaces terminating abruptly adjacent the juncture of the base flange and rail web to provide an abutment for limiting the movement of the splice bars of the other section.

In testimony whereof I affix my signature in presence of two witnesses.

JEROME N. ADAMS.
